(57) **CLAIM**

The ornamental design for a hockey protective pad for back as shown and described.

DESCRIPTION

1. Hockey protective pad for back

1.1 : Perspective

1.2 : Left

1.3 : Front

1.4 : Right

1.5 : Back

1.6 : Top

1.7 : Bottom

The design consists of the visual features of the hockey protective pad for back shown in the drawings. The dot-dash broken lines define the boundary of the claimed design and form no part of the claimed design. The drawings contain a symbolic break. The portion between the break lines forms no part of the claimed design. The dash-dash broken lines depict portions of the hockey protective pad for back that form no part of the claimed design. FIG. 1 is a perspective front top view of a hockey protective pad for back showing the design. FIG. 2 is a left side view of the design thereof. FIG. 3 is a front view of the design thereof. FIG. 4 is a right side view of the design thereof. FIG. 5 is a back view of the design thereof. FIG. 6 is a top view of the design thereof. FIG. 7 is a bottom view of the design thereof. Drawings of the design are included.
